UNITED STATES PATENT OFFICE.

WILLIAM J. ALLEN, OF ST. CLOUD, MINNESOTA.

TABLE FOR CARRYING STONE FOR CUTTING.

Application filed September 7, 1926. Serial No. 133,874.

This invention relates to a table and particularly to a table adapted to support a stone, while the same is being presented to a cutting saw or knife. Such stones are usually 5 of great weight and it has heretofore been a difficult operation to properly adjust the table to have the desired angle on the stone and to have the same properly presented to the cutting tool.

10 It is an object of this invention, therefore, to provide a table adapted to carry a stone having means by which the same can be quickly and easily tilted and transversely adjusted so that the stone is presented to the 15 cutting tool in the desired manner.

It is a further object of the invention to provide such a table centrally mounted on a supporting member transversely movable on a base member, which base member prefer- 20 ably is in the form of a truck, means being provided for raising and lowering the corners of said table and also for moving said supporting member transversely.

It is a further object of the invention to 25 provide such a device as set forth in the preceding paragraph with operating means at one side of the table for tilting the same and moving the same transversely.

These and other objects and advantages of 30 the invention will be fully set forth in the following description made in connection with the accompanying drawings, in which like reference characters refer to similar parts throughout the several views and in which:—

35 Fig. 1 is a view partly in side elevation and partly in vertical section of the device;

Fig. 2 is a view in horizontal cross-section taken substantially on line 2—2 of Fig. 1, as indicated by the arrows; and

40 Fig. 3 is a vertical section taken on line 3—3 of Fig. 2, as indicated by the arrows.

Referring to the drawings, a device is 45 shown comprising a base member 5 of general rectangular shape in plan. While the device 5 may be variously constructed, in the embodiment of the invention illustrated it is shown as formed of channel bars having their webs vertical and their flanges disposed horizontally. Axles 6 are mounted in and extend 50 transversely of the member 5 adjacent the ends thereof, on which axles are mounted the wheels 7 adapted to run upon the rails 8. The member 5 has a pair of spaced channel members 5^a extending transversely thereof at each side of its center, having their flanges directed away from each other, the upper

sides of which form tracks for truck wheels 9. The truck wheels 9 are mounted on axles 10 carried in a small truck or frame member 11 having secured thereto a bearing 12 from 60 which upstands a pin or standard 13. A table 14 is provided comprising a top plate having channel members 14^a extending thereabout beneath its edges. A pair of channel bars 14^b extend transversely beneath the table 14 65 at each side of the center, between which is secured a bearing 14^c having a conical recess therein loosely receiving the upper end of the standard 13, so that there will be enough play between the bearing 14^c and the upper 70 end of standard 13 to permit the bearing and parts to which the same is fixed to be tilted in any direction in respect to the standard. Angle brackets 15 are secured at each end of the channel members 14^a at the corners of the 75 table 14 and carry small cups 15^a within which are mounted the upper ends of screws 16 extending downwardly from said brackets. The screws 16 pass through nuts 17 having beveled gears 17^a formed on their upper sides. 80 The beveled gears 17^a are journaled in bushings 18 and supported on flanges 18^a at the top of said bushings. A frame member 19 of substantially the same size and shape as the frame of member 5 is formed of channel 85 bars having their flanges extending outwardly and resting on the channel bars forming the frame 5, as clearly shown in Fig. 1. The frame 19 has channel bars 20 spaced from the ends thereof and extending parallel thereto and the bushings 18 are supported between channel bars 20 and the ends of the frame 19, as clearly shown in Figs. 1 and 3. The beveled gears 17^a mesh with the beveled gears 21. The beveled gears 21 at one side of the 90 table are secured to shafts 22 journaled in bearings 23 carried on and secured to brackets 24, which in turn are supported on the channel members 20. The shafts 22 are connected by a universal joint 25 to shafts 26 100 extending to one side of the table 14 and member 19 and journaled in bearings 27 secured to the side of the frame member 19, said shafts having hand wheels 28 secured thereto at the outer ends thereof and disposed at one side of the table 14 and frame member 19. The gears 21 at the other side of the table are secured to shafts 29 journaled in bearings 30 secured to the sides of the frame member 19, said shafts having hand wheels 28 105 secured at their outer ends which are also disposed at one side of the table 14 and frame

member 19. Each channel member 20 has a headed and nutted bolt 32 extending centrally therethrough which is embraced by a slot 33^a formed in one end of a lever 33 pivoted intermediate its ends on a headed and nutted bolt 34 carried in a channel member 35 extending between and secured to the sides of base member 5. The lever 33 has a slot 33^b at its other end which embraces a stud 36 extending upwardly from a nut 37. The nut 37 is engaged by a screw 38 extending between and journaled in the sides of frame member 5, which screw has a hand wheel 39 disposed at one side of the base member 5.

15 In operation the stone to be cut will be supported on the table 14 and the same will be moved up to the cutting knife or saw by traversing the truck 5 on the rails 8. If the stone is not disposed on the table as desired, the table may be variously moved to bring the stone into the desired position relatively to the cutting tool. If one of the hand wheels 28 or 31 is rotated, one of the screws 16 will be raised. If one of the screws 16 at one corner is raised, the screws at the other corners will be correspondingly lowered by properly turning the hand wheels connected thereto. The table will thus be tilted about its central support 13 and any one of the corners can thus be raised to give the stone the desired position. If it is desired to swing the table laterally, that is, to move its central longitudinal axis at an angle, one of the hand wheels 39 will be turned. If one of the 35 said hand wheels is turned, its lever 33 will be swung about its pivot 34 and one end of supporting member 19 will be moved transversely of frame 5. When only one of the hand wheels 39 is thus moved, the frame 19 will move laterally and pivot about the bolt 32 of the other lever 33, the truck 11 and wheels 9 moving longitudinally on the frame 5. If the frame 19 is to be moved bodily laterally, that is, if both ends of the same are 40 to be moved, both of the hand wheels 39 may be operated and the table will then move transversely of the frame 5, the wheels 9 rolling on said frame. It is thus seen that the table may be tilted in any direction and may be moved laterally at one or both ends in order to bring the stone 7 to the desired position. The movements of the table are easily and quickly made by turning of the hand wheels and the stone is quickly brought to the 45 desired position. Heretofore it has been necessary to tilt the stone by wedges or other means necessitating considerable time and labor.

From the above description it is seen that 50 applicant has provided a very simple and efficient stone supporting table and one by means of which the stone to be cut could quickly and easily be brought to the proper position. The device comprises few parts 55 and can be easily and inexpensively made

and at the same time be made very durable. The device has been amply demonstrated in actual operation and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. A stone supporting device having in combination, a base, a supporting frame disposed on said base, a member bodily movable transversely on said base, a table centrally mounted on said member and bodily movable therewith, means at the corners of said table for raising and lowering the same including operating hand wheels disposed at one side of said table and means for horizontally moving either or both ends of said supporting frame transversely of said base, including hand wheels disposed at one side of said table.

2. A stone supporting device having in combination, a base comprising a truck having supporting wheels thereon, a frame mounted on said base, a truck member transversely movable of said base adjacent the center thereof, a standard carried by said truck frame, a table centrally mounted on said standard, screws at the corners of said table for raising and lowering the same, operating means for said screws carried on said frame including hand wheels disposed at one side of said frame and means for moving one end of said frame laterally comprising a lever pivoted on said base and connected at one end to said frame and a screw having an operating hand wheel thereon connected to the other end of said lever.

3. A stone supporting device having in combination, a base member comprising a truck, a wheeled frame carried on said base and movable transversely of said base at the center thereof, supporting means carried by said wheeled frame, a table centrally mounted on said supporting means, screws secured beneath the corners of said table and extending downwardly therefrom, nuts engaging said screws, a frame carried on said base in which said nuts are mounted, gears for rotating said nuts to move said screws, hand wheels disposed at the sides of said table for operating said gears, and means for moving said supporting frame transversely of said base.

4. The structure set forth in claim 3, said last mentioned means comprising levers fulcrumed to said base member at each side of said wheeled frame, having slots at their ends engaging means at the ends of said supporting

frame and having nuts at their other ends, screws extending transversely of said base engaging said nuts and having hand wheels at one side of said base for rotating the same.

5. A stone supporting device having in combination, a base, a supporting frame mounted therein, a table carried by said frame, means on said frame for tilting said table to a desired inclined angle with said frame, and means for moving either or both ends of said table transversely of said base without varying the angle of inclination of said table.

10. A stone supporting device having in combination, a base, a supporting frame mounted thereon, a truck mounted on said base for transverse movement thereon, a table carried by said truck, means mounted on said frame for tilting said table on said truck to a desired inclined angle in respect to said

frame, and means for moving either or both ends of said frame and table transversely of said base without varying the angle of inclination of said table.

15. A stone supporting device having in combination, a base, a supporting frame mounted on said base, a carriage mounted on said base and transversely movable thereon, a table centrally mounted on said carriage for rotation in respect thereto and for tipping movement in respect thereto, means extending upwardly from said frame, bearing against said table and operable to tip the same to a desired angle of inclination with said frame, and means operable to move either or both 20 ends of said frame and table transversely of said base without changing the angle of inclination of said table.

In testimony whereof I affix my signature.

WILLIAM J. ALLEN.
